EXTRACTION PROCESS AND APPARATUS

Bert B. Beeson, Piqua, Ohio, assignor to The French Oil Mill Machinery Company, Piqua, Ohio

Application November 30, 1946, Serial No. 713,377

8 Claims. (Cl. 260—412.4)

1

This invention relates to extraction of liquids from materials such, for example, as the solvent extraction of fatty or oily substances from meat scraps, vegetable seed meals and other fat or oil bearing materials.

In the solvent extraction of the fat or oil contained in materials, such for instance, as meat scraps and the meal of vegetable seeds, a well known practice is to pass a volatile liquid solvent through the fat or oil bearing material while it is held or confined in the containers. This practice can be conducted in a batch system in which the material is treated in different batches in a container, or it can be effected in a continuous system in which a series of containers carrying the material move in succession in an endless or closed circuit, the solvent being applied to the material to percolate or drain therethrough in the successive containers during their travel in the circuit. The completeness of extraction depends upon various considerations, including the condition of the fat or oil bearing material, the solvent temperature and other conditions, and it also depends to a very considerable extent on the quantity of solvent which is applied to and drains through the material and on the amount of solvent retained in or failing to drain from the fat or oil bearing material. In a continuous system, the capacity of a unit depends, among other things, on the rate at which the solvent will drain through the material, commonly termed the "drainage rate," and on the amount of solvent retained in the spent treated material, commonly termed the "solvent retention."

One object of the invention is to improve and materially increase the capacity and efficiency of extraction processes and apparatus by increasing the drainage of liquid from and decreasing its retention by material while held in a container or containers.

While this invention is especially suited for use in solvent extraction processes and apparatus of the continuous system type, it is not restricted in its various possible applications to such solvent extraction processes and apparatus.

Another object of the invention is to effect the stated improved results by applying a vibrating or agitating force to containers for transmission to fat or oil bearing material therein to increase the drainage of a solvent through and from the material and reduce its retention in the material. It would naturally be expected by skilled engineers and mechanics versed in the art of solvent extraction that to thus vibrate or

2

agitate the material would tend to pack it or make it denser and reduce the drainage of solvent therethrough, but I have discovered, on the contrary, that the application of a vibrating or agitating force to the containers of the material produces an unexpected, greatly increased rate of drainage of the solvent through the material and materially reduces the amount of solvent retained in the material.

10 The accompanying drawings illustrate a preferred embodiment of apparatus embodying my invention and for carrying out my improved process, but it is to be understood that the drawings and following description exemplify only one 15 of various different applications of the invention, and are not intended to limit the scope of the invention, which is set forth in the appended claims.

19 In said drawings:
20 Fig. 1 is a front elevation of a solvent extractor of the vertical tower or elevator type embodying the invention.

Fig. 2 is a side elevation thereof.

Fig. 3 is a fragmentary, front, sectional elevation thereof, on an enlarged scale.

25 Fig. 4 is a sectional elevation showing one of the vibrators for the material container.

30 The extraction apparatus as illustrated in the drawings is of the known tower or elevator type having an upright housing or casing 10 providing a high chamber within which is an endless travelling elevator or conveyor including a series of containers or baskets 11 for the material to be treated, arranged to travel in succession upwardly and downwardly in an endless circuit of 35 the chamber. The fat or oil bearing material may be introduced as usual into the travelling baskets or containers prior to each upward passage thereof in the chamber, and the solvent is applied or delivered to the material in the baskets for drainage through the material during the upward travel of the baskets, the material after the solvent has drained therefrom being discharged from the baskets in succession and 40 replaced by new material after the completion of each ascent of the baskets and prior to the beginning of their next ascent in the chamber.

45 As usual, the baskets or containers are provided with perforated or open mesh bottoms 12 and, 50 as shown, are mounted in spaced relation between a pair of parallel endless conveyor or sprocket chains 13 which pass around pairs of sprocket wheels 14 and 15 rotatably mounted respectively in lower and upper portions of the 55 housing. Preferably, the top pair of wheels 15 is

located in the top portion of the housing at one side of the elevator chamber, and the conveyor chains extend obliquely downwardly and inwardly from this top pair of wheels and pass over pairs of guiding wheels or sprockets 16 and 17 located below and to one side of the top wheels 15, from whence the chains extend downwardly to the bottom pair of wheels 14. By this arrangement of the conveyor, the topmost wheels for the conveyor chains are offset laterally to one side of the main ascending and descending portions of the conveyor whereby they are located over or above a discharge hopper 18 formed or provided on an offset side portion of the elevator housing, so that each basket, in being carried by the conveyor chains around the top sprockets, is inverted above the discharge hopper in position for the material in the basket to drop therefrom into the discharge hopper for discharge from the elevator housing.

Each pair of supporting and guiding sprockets or wheels for the conveyor chains may be secured on a shaft journalled in suitable bearings on the housing, and one of the shafts, as the shaft 19 for the top wheels 15, may be driven for driving the conveyor, as by a drive wheel 20, secured to the shaft outside of the housing. The shaft for one pair of wheels, for example, the bottom pair 14, may be journalled in bearings 21 which are adjustably mounted on the housing to permit adjustment of the shaft, as by adjusting screws 22 for maintaining the conveyor chains under suitable tension.

The solvent or miscella is preferably applied to the material in the baskets during their upward travel in the treating chamber, as by means of one or more valve-controlled spray pipes 23 arranged to deliver the solvent from a suitable tank or source of supply and spray it on the top of the material in each basket as the basket travels past the spray pipe or pipes. The solvent is allowed to percolate or drain through the material in the baskets and discharge through their perforated bottoms during their upward travel in the treating chamber, the solvent preferably dripping from the bottom of each basket into the next basket below, and finally into the bottom of the treating chamber from which the solvent or miscella may be removed in the usual or any suitable manner.

In order to increase the rate of drainage of the solvent through the fat or oil bearing material and ensure a decreased retention of solvent in the material, the baskets or containers 11 are subjected to a vibrating or agitating force during or after the application of the solvent to the material. By preference, for this purpose, each container or basket, during its upward travel in the treating chamber, passes by one or more vibrating devices 25 by means of which the basket is subjected to the vibrating force, to thereby agitate the material in the basket. In the apparatus as shown, one such vibrator is located below the lowermost solvent spray pipe 23, and other vibrators are arranged one above each solvent spray pipe, so that the vibrators are adapted to vibrate the baskets both before they reach and after they pass each of the spray pipes. The vibrators may be alike and of any suitable type or construction adapted to subject the containers or baskets to vibrating or agitating force for transmission to the material therein during the travel of the containers or baskets past the vibrators. In this way, each container is vibrated or agitated during and after the time that the solvent is being applied

to the material therein from each of the spray pipes, and also while the solvent or miscella is dripping into one container from another container above, during the upward travel of the containers.

The vibrators shown in the drawings are of a known, pneumatically operated type, each comprising a piston 26 reciprocated in a cylinder 27 by pressure fluid supplied to the cylinders, as by a pipe 28, so that the piston will strike blows alternately on opposite ends or heads of the cylinder and thereby produce forcible vibrations of the cylinder. Each vibrator 25 is suitably mounted, preferably by means of a resilient shock absorbing base or support 29 exteriorly on the elevator housing, and the vibratory cylinder is operatively connected to or associated with a plunger 30 which passes through and is capable of limited reciprocation in a suitably packed hole 31 in the adjacent wall of the housing for transmitting the vibrations of the vibrator to the conveyor baskets 44 as they travel past the plunger. The plunger may be provided at its inner end with a vertical plate or shoe 32 positioned so as to contact with or engage a shoe or plate 33 on the adjacent side of each conveyor basket as the basket passes the vibrator plunger. The plunger shoe is shown of a vertical length somewhat greater than the distances between adjacent conveyor baskets, so that one basket will contact with the lower portion of the plunger shoe before the next basket above passes clear of the upper portion of the shoe. In this way, each basket will remain in operative engagement with the plunger shoe during a substantial distance of the travel of the basket and will be subjected during this time to the vibrating or agitating force of the vibrator. The plunger shoe 32 may be provided with an outwardly bent lower end, and each basket shoe 33 provided with an inwardly bent upper end so as to guide the baskets into operative contact with the vibrator shoe and prevent possible interference of the vibrator with the travel of the baskets past the same.

I have also found that by similarly subjecting each conveyor basket to vibrating force when it is inverted over the discharge hopper 18, a very quick and complete emptying of the spent oil bearing material from the basket into the hopper is ensured. The vibrator 25a shown for this purpose may be and preferably is of like construction and operation to those above described for increasing the solvent drainage. Vibration of the baskets by such a vibrator has proved to be much more effective in thoroughly and quickly emptying the basket of its contents than striking the inverted baskets a blow with a knocker.

The application of a vibrating force to the baskets in such manner as hereinbefore explained greatly accelerates the drainage rate, making it practicable to apply much more solvent or miscella than it would otherwise be possible to get through the flakes or particles of the material undergoing extraction. The fat content is consequently reduced much more rapidly than has been possible heretofore and the capacity of such an extraction unit is greatly increased. The rate of vibrations of the baskets or containers may vary through a range from a very slow rate of only a few per minute to a very rapid rate per second, but a medium rate of about 1200, more or less, per minute is preferred.

As before explained and shown in the drawings, one of the vibrators may be arranged to

act on the baskets or containers at a position thereof above that where the solvent is supplied to the material. This second stage vibration is a useful contribution to the art of extraction because it decreases the amount of solvent retained in the material and the solvent carries some fat in it; and it also reduces the application of heat to the extracted material necessary to drive off the retained solvent.

My invention can be applied profitably in the extraction of fatty substances or liquids from various different materials, particularly any material which is in such condition that solvent or liquid drainage therethrough is too slow for successful commercial extraction, or the liquid retention is high. Examples are cotton seed, flax seed, peanuts, copra. But the invention is also applicable to liquid extraction from other materials and to other processes, not herein specifically mentioned. Any of the commonly used solvents, such as hexane, heptane, ethers, alcohols, etc. can be used in a process or apparatus according to this invention.

In the claims of this application, the term "perforated bottoms," as applied to the containers or baskets is intended to include bottoms or other appropriate portions of the containers of any mesh, porous or permeable character which will allow the required discharge from the containers of the solvent or liquid draining from the material therein.

I claim as my invention:

1. A process of solvent extraction of fatty oils from oleaginous material, comprising applying a solvent for the fatty oils to the top of a confined body of the material, draining off from the bottom of said body, the solvent that seeps through the material, and regularly, horizontally and repeatedly vibrating said confined body and the seeping solvent therein to increase the rate of drainage of the solvent through the material.

2. A process for solvent extraction of fatty oils from oleaginous materials in loose particles, which comprises conducting said materials in confined batches in succession along a selected path, depositing a solvent liquid on the tops of said batches in succession, and draining it off after it has percolated through each bath, and successively locally and repeatedly vibrating said batches with periodic regularity while still confined, in horizontal directions crosswise of said path during travel of that batch along a selected portion of said path while said liquid is passing therethrough, to increase rate of drainage therethrough.

3. A process of solvent extraction of fatty oils from oleaginous material, comprising carrying the material in batches in succession in a circuit in a portion of which they move in an ascending path, applying a solvent for the fatty matter to the top of the material in each batch for drainage therethrough during said ascending movement of the batches, draining off the solvent from each batch during the ascent, and locally and horizontally vibrating the ascending batches with solvent with periodic regularity to increase the drainage of the solvent through and from the material.

4. A process of solvent extraction of fatty oils from oleaginous material, comprising carrying the material in batches in succession in a circuit in a portion of which the batches move in succession one above another in an ascending path, applying the solvent for the fatty matter to the top of the material in the batches in suc-

cession, discharging the solvent from each batch during their said ascending movement upon the top of the batch next below it, and horizontally and repeatedly vibrating the ascending batches with periodic regularity at locations in their ascending movement both below and above the point of application of the solvent to the material for increasing the drainage of the solvent through and from the material.

5. In a solvent extraction apparatus of the type having a housing, an endless flexible conveyor, and a series of containers attached to said conveyor in succession therealong, carrying oil bearing material and having perforated bottoms, said conveyor carrying said containers upwardly and downwardly in a circuit in said housing, the improvement therein which comprises the combination therewith of delivery pipes for applying an oil solvent to the material in said containers during their upward travel in the housing for drainage through the material, and a vibrator disposed at the side of said upwardly moving containers and having a horizontally movable vibrating element with an upright shoe along the path of travel of the containers and engaging in succession with the sides of said upwardly moving containers for imparting thereto repeated horizontal vibrations to thereby increase the drainage of the solvent through the material in the containers.

6. In a solvent extraction apparatus of the type including a housing, an endless conveyor therein, and a series of containers attached to said conveyor in succession therealong and carrying oil bearing material and having open tops and perforated bottoms, said conveyor having vertically movable stretches for carrying said containers upwardly and downwardly in an endless circuit in said housing, a liquid discharge pipe for discharging an oil solvent upon the material in said containers in succession during their upward travel in the housing for drainage through the material, said housing having a discharge hopper over which said containers move in inverted position in succession at the end of their ascent and the start of their downward travel for discharging material from the containers in succession into said hopper, the addition thereto of a vibrator with a horizontally vibrating element in said housing engaging with said containers in succession during their ascent to horizontally vibrate said ascending containers and thereby increase the drainage of the solvent through the material in the ascending containers, and a vibrator with a horizontally vibrating element in said housing engaging with said containers in succession while in their inverted position above said hopper at the end of their ascent and the start of their descent to facilitate the discharge of the material from the containers into the hopper.

7. An apparatus for extracting oily matter from oil bearing materials comprising an elongated vertically positioned container having inlet and outlet conduits attached thereto, said container surrounding an endless belt conveyor having a series of perforated buckets attached thereto adapted to travel about a certain fixed axis and within said container, and a vibrator having a vibratable horizontally operating element attached to the wall of the container arranged in position to impart vibrations to said buckets so as to increase the drainage of the solvent used in the extraction, through and from the material.

8. An apparatus for extracting oily matter from

oil-bearing materials comprising a housing, an endless belt conveyor within said housing and carrying in succession thereon a series of perforated buckets which move with the conveyor in a selected path, with the buckets upright and rising on one stretch of the conveyor and inverted over a hopper and descending on another stretch of the conveyor, a vibrator carried by said housing and having a generally horizontally vibratable operating element carrying a shoe engageable in succession with the inverted buckets over said hopper for vibrating the inverted buckets in succession, to dislodge adhering materials, another vibrator carried by said housing and having a generally horizontally vibratable operating element carrying a shoe, said shoe extending along the path of travel of the rising buckets for engagement with the rising buckets in succession to impart vibrations thereto, and liquid delivery means for depositing a solvent into the rising buckets in succession during at least part of their ascent.
